UNITED STATES PATENT OFFICE.

ERNEST MONTGOMERY SYMMES, OF BACCHUS, UTAH, ASSIGNOR TO HERCULES POWDER COMPANY, OF WILMINGTON, DELAWARE, A CORPORATION OF DELAWARE.

PROCESS OF PRODUCING SODIUM SULFID.

1,289,016.

Specification of Letters Patent.

Patented Dec. 24, 1918.

Application filed June 9, 1917. Serial No. 173,738.

To all whom it may concern:

Be it known that I, ERNEST MONTGOMERY SYMMES, of Bacchus, in the county of Salt Lake, and in the State of Utah, have invented a certain new and useful Improvement in Processes of Producing Sodium Sulfid, and do hereby declare that the following is a full, clear, and exact description thereof.

My invention relates particularly to a process for the production of sodium sulfid from niter cake.

The object of my invention is to provide a process for producing sodium sulfid from niter cake in such a manner as to avoid the corrosion of the furnace lining in the process and so as to avoid consequent contamination of the product as the result of any such corrosion. Hitherto, furnaces in which sodium sulfids were produced were lined with fire bricks but such furnace linings could not resist the attack of the materials in contact therewith. It was necessary therefore, for them to be often replaced and they formed in addition a source of contamination in the sulfids produced.

The object of my invention is to avoid these disadvantages and to carry out the process in connection with a furnace the walls of which cannot be corroded by the materials.

The object of my invention is furthermore to carry out the process in connection with a furnace lined with corrosiron which I have discovered is not attacked by the fused alkali sulfids, free sulfur, etc., present even at a bright red heat.

Further objects of my invention will appear from a detailed description thereof contained hereinafter.

While my invention is capable of being carried out in many different ways for the purpose of illustration I have described herein only one manner of carrying out the same, and while the process may be carried out in connection with different types of apparatus I have shown only one type of suitable apparatus in the accompanying drawings, in which—

Figure 1 is a longitudinal section of a furnace in which my invention may be carried out;

Fig. 2 is a transverse section of the same; and

Fig. 3 is a horizontal section of the furnace taken on the line 3—3 of Fig. 1. 55

In the drawings I have shown a furnace comprising furnace walls 1 having a stoke hole 2 communicating with a grate 3 having a passage way 4 leading to a furnace chamber 5 having in the upper portion thereof a large ladle 6 supported upon trunnions 7, one of which has a long extension 8 to enable the ladle 6 to be dumped so as to discharge its contents into a trough 9 which may be extended through an opening 10 65 into the chamber 5 beneath the ladle 6. The ladle 6 is made of corrosiron, that is to say an alloy of iron and silicon, containing at least 15% of silicon and which may amount to 20% of silicon. The furnace gases pass 70 from the chamber 5 through a passageway 11 to a chamber 12 and thence into a stack 13 having a damper 14 which may be turned to regulate the draft.

In carrying out my process I fuse together at a red heat 4 parts of niter cake, that is to say acid sodium sulfate with one part of ordinary salt or such proportions of niter cake and salt as will give the neutral salt after fusion of the two thus producing 80 a neutral cake. This operation may be carried out in any ordinary type of furnace and is not intended to be carried out in the furnace shown in the drawings. Thereafter the neutral cake thus obtained is mixed together with powdered coke in the following proportions: Neutral cake 63 parts, powdered coke 37 parts, and the mixture is introduced into the ladle 6 and fused therein to approximately a temperature of 888° C. 90 The coke reduces the sodium sulfate in the cake so as to produce sodium sulfid. Because of the material of which the ladle 6 is made the fused substances including alkali sulfids, free sulfur, etc., do not attack 95 the material of the ladle at all and the ladle will therefore last for an indefinite period for this purpose and the sodium sulfid produced is not contaminated in any way by having been produced in the ladle 6. When 100 the reaction is complete the ladle 6 is turned upon the trunnions 7 and 8 so that the contents may be conducted away by means of the trough 9. The sodium sulfid thus obtained may be purified in any desired manner, as by leaching, etc.

105

While I have described my invention above in detail I wish it to be understood that many changes may be made therein without departing from the spirit of my invention.

5 What I claim is:—

1. The process which comprises producing a sulfid by fusion of a sulfate with carbon in a container of corrosiron.

2. The process which comprises producing a sulfid by fusion of sodium sulfate with coke in a container of corrosiron.

In testimony that I claim the foregoing I have hereunto set my hand.

ERNEST MONTGOMERY SYMMES.
